UNITED STATES PATENT OFFICE.

EMANUEL EINSTEIN, OF NEW YORK, N. Y.

DESIGN FOR NAP-SURFACE OF CLOTH.

SPECIFICATION forming part of Design No. 12,295, dated June 7, 1881.

Application filed March 14, 1881. Term of patent 3½ years.

To all whom it may concern:

Be it known that I, EMANUEL EINSTEIN, of New York city, have designed a new and original Design for the Nap-Surface of Cloths, of which the following, in connection with the accompanying drawing, is a full, clear, and exact description.

This design is related to that class of designs which are intended to be cut into the nap or pile of smooth-finished cloths in the act of shearing the same, such as is shown in the patent of Felix Samson, dated February 15, 1881, No. 12,176; and while these designs might be produced on the cloth in other ways than cutting, yet no other mode is contemplated or is so desirable, as a very agreeable and novel effect is obtained by the contrast of the sharply-cut grooves or figures with the smooth, level nap of the cloth.

My present design is one of several of the aforesaid character filed on the same date as this; and it consists in a special form and arrangement of lines or grooves, producing a new effect, as hereinafter set forth.

The figure in the drawing gives a face view

of a piece of cloth finished according to my design.

In this figure the field of the design consists of the smooth or finished nap of the cloth, forming a uniform, level surface, while the lines represent grooves cut into this nap.

The design, as may be now observed, is composed of one or more wavy or serpentine lines or grooves, *a a*, extending lengthwise along the cloth at intervals, leaving comparatively wide bands *b b* of smooth nap between them, with a broadly-bent zigzag line or groove, *c*, extending to and fro along the said bands, as illustrated, thereby producing a very striking and unique effect.

What I claim is—

The design for the nap-surface of cloth, consisting of parallel bands decorated with a to-and-fro zigzag line, alternating with longitudinal serpentine lines or stripes, substantially as described and illustrated.

EMANUEL EINSTEIN.
